DYNAMIC COMPASS

Jean-Léon Reutter, Paris, France; vested in the
Alien Property CustodianApplication January 3, 1940, Serial No. 312,220
In France January 4, 1939

5 Claims. (Cl. 33—222)

The present invention, relates to compasses comprising, in combination, a magnetic needle oscillating on a pivot, generally vertical, and means for ensuring the maintenance of its oscillations by impulses imparted to the needle at a point located in the immediate vicinity of the lubber's point of the compass; but whereas in compasses of this type already known, the orientation of this lubber's point was deduced from the comparison between the periods of oscillation of the magnetic needle on the one hand, and of a nonmagnetic rocking unit on the other hand, on the contrary, the invention determines the orientation (or a change of orientation) by the comparison between the relative durations of the two half-oscillations of the magnetic needle. It is in fact to be noted that these two half-oscillations are of equal duration when the lubber's point coincides with the magnetic North-South position, and that thereby, the sustaining impulses are imparted to the needle when the latter is set in the direction of the terrestrial magnetic field; but that this is no longer the case when the lubber's point departs from the magnetic meridian, the difference between the two half-oscillations being so much the greater as the angle formed between the lubber's point and the magnetic meridian is itself greater.

The comparison between the durations of the two half-oscillations can be effected by any mechanical, electric or pneumatic control device for instance; it is however to be noted that the energy for the control is taken not from the magnetic needle, but from the members which maintain its movement. Thus, any desirable energy can be obtained mechanically or electrically without modifying the mean position of the needle. Accessorily, it will be noted that the invention eliminates all difficulties due to the friction of the pivots and to the necessity of providing a system for damping the oscillations of the needle in the usual compasses.

The invention can take the form of a number of embodiments, which it obviously includes in its scope and which can differ from each other in particular by:

1°—The means used for maintaining the movement of the magnetic needle.

2°—The means used for controlling said movement and for deducting therefrom the North-South direction.

The means for maintaining the oscillations can be mechanical, electric or pneumatic. All known mechanical escapements can be used, the spiral-balance wheel system being replaced by the mag-

netic needle-magnetic field system. The power actuating the escapement can be of any origin whatever. The direct electric maintenance of the oscillations can, according to the invention, take place by superposing, at regular intervals, and at the suitable instant, an electromagnetic field to the terrestrial field, by means of a coil arranged in the vicinity of the magnetic needle. These means will be described hereinafter.

10 The pneumatic maintenance can be effected either by the pneumatic winding-up of a spring driving a mechanical escapement, or by the direct action of an air jet on a wheel provided with fins rigid with the shaft of the escapement wheel, or again, by the direct action of an air jet on a blade rigid with the shaft of the oscillating magnetic needle.

20 Devices in accordance with the invention will be described hereinafter, which constitute entirely mechanical, electric or pneumatic embodiments, but various maintenance methods must be mentioned which, without departing from the scope of the invention, and generally by a very simple adaptation, can be combined with the 25 different control methods.

Another particularity of the invention consists in the fact that, if the oscillation period of the needle obviously depends on the intensity of the horizontal component of the terrestrial magnetic field, the ratio between the durations of the two half-periods from the point of impulse is constant for a given amplitude. This remark is important in the case of a movable object (aeroplane, ship) moving from the poles towards the 30 equator, resulting in a constant increase of the horizontal component of the field.

The invention includes in its scope all applications which can be made thereof, but more particularly:

40 1°—The application of all the means making it possible to obtain a distant head indicator and a telecompass.

2°—The application of said means to the control of the gyroscope of an automatic pilot or of 45 an orientation gyroscope.

3°—The application of said means to the mechanical control of an aeroplane without the intervention of a gyroscope.

A diagrammatic description of the various 50 solutions will be given hereinafter; and as all the members mentioned as well as their functions are well known to those skilled in the art, a detailed description of said members is hardly necessary.

Referring now specifically to the accompanying drawings forming part hereof,

Fig. 1 illustrates an embodiment of the invention using a mechanical clock type escapement having a spiral spring.

Fig. 2 is a modification omitting the spring.

Fig. 3 illustrates electrical apparatus embodying the invention in a system using a double winding to influence a magnetic needle.

Fig. 4 is a modification using a single winding to influence the needle.

Fig. 5 is a detail modification showing how a contact can be used to influence the needle, the other portions of the system being omitted to simplify the view.

Fig. 6a illustrates a pneumatically actuated apparatus using a watch type escapement for operating a magnetic needle according to the invention, while Fig. 6b illustrates a further modification from another point of view.

Fig. 7 is a modification showing in part how a pneumatic turbine can be driven by two air jets.

Fig. 8 also illustrates a modification of the pneumatic form of the invention showing how the magnetic needle may be directly actuated by an air jet.

Fig. 9 is a particular mechanical form of embodiment of the invention including electrical indicator means to carry the indications of the device to a distance.

Mechanical apparatus (Figs. 1 and 2).

In Fig. 1, a magnetic needle 1 movable about its axis (end view in the figure) carries a plate pin 2 which receives, as in an ordinary lever escapement, impulses from the fork 3. The latter carries, at the end of an extension, a wheel 4 meshing with a wheel 5 the axis of rotation of which is in alignment with that of the fork.

For greater clearness, the escapement wheel, the set of wheels which actuates it, the driving spring and the lever are not shown. In the immediate vicinity of the wheel 4 are provided two driving wheels 6 and 7 continuously rotating in reverse directions to each other, and so arranged that at every rocking movement of the fork 3, the wheel 4 comes in contact with one of said wheels 6 or 7 which drives it. The operation is consequently as follows:

If the pin of plate 2 receives the impulses when the needle 1 is set on the magnetic meridian *a*—*b*, the two half-periods are equal and the wheel 4 is in contact for equal durations with wheel 6 and wheel 7; it will have a reciprocating movement of very small amplitude, but will not rotate. On the contrary, if the apparatus effects, as a whole, a movement of rotation about a vertical axis (end view in the figure) and if the position of the magnetic needle at the moment of the impulse becomes *c*—*d* instead of *a*—*b*, the contact of the wheel 4 with the wheels 6 and 7 will be of unequal duration, and the wheel 4 will have, as well as wheel 5 a movement of rotation in a definite direction which would be reversed if the mean position of the needle became *e*—*f* instead of *c*—*d*. This movement of rotation will last as long as *c*—*d* or *e*—*f* are different from *a*—*b*. This indication can be put in evidence by an index 8 moving over a dial 9.

This apparatus is a simple indicator of the heading when a spiral spring 10 is added to the wheel 5, said spring tending to restore the index 8 to the zero of the dial. The spiral spring 10 introduces a balance for lever 3 with respect to wheel 5, the lever being taken as normally vertical and one end of the spring connected to the pivot shaft of the lever and the other end to

the wheel so that it forms a very resilient connection between said lever and wheel.

Hence, during the interval occupied by the wheel 4 to pass from contact with wheel 6 to that with wheel 7, the spiral, or spring 10, if there is a deviation of index or pointer 8, tends to cause the latter to go back towards 0 and the more energetically as the deviation is greater. The rotation of index 8 is limited to a certain value which measures the variation or divergence relatively to the head initially chosen by adjusting or shifting the device as a whole, and for which the index was at zero. In Fig. 2, the spiral spring has been done away with, wheel 5 meshes with a wheel 11, meshing in its turn with a toothed crown wheel 12. This crown wheel is assumed to be connected to the movable object (aeroplane or ship) whereas the unit constituted by members 1 to 11 is movable about a vertical axis passing through the centre of the wheel 5. In this case, the rotation of wheel 5 would determine, relatively to the movable object, the rotation of the entire device in such a direction that the magnetic needle 1 will gradually return to the position north-south, which would cause the rotation to cease. A real compass is thereby obtained the indications of which can be transmitted to a distance by a contrivance such as a Bowden cable, transmission by endless wire, etc.

30 Electric apparatus

In Fig. 3, 20 illustrates a magnetic needle carrying a contact 21 and electrically connected to the body of the apparatus by a spiral spring 22. In the vicinity of 21 are arranged two electrodes 23 and 24 which, at each half-oscillation come alternately in contact with 21, thus alternately closing the circuit of the two coil windings 25 and 26 of a relay having current reversing contacts 27, through two coils or windings 28 and 29 adapted to create about the magnetic needle 20 alternately, a west-east and an east-west field the function of which is to maintain the movement of the needle 20. The device is supplied by any source whatever of direct current 30.

The contacts of relay 27 reverse at every half-period the direction of the current from the source 31 into the polarized ammeter 32, so chosen that its movable unit has a rather great inertia and a period of oscillation of its own, which is rapid relatively to that of the magnetic needle. A large capacity 33 can be added to the terminals.

If the contact of 21 with 23 and 24 takes place in the neutral or central position of the needle, the relay closes its contacts for equal durations in one direction as well as in the other, and the polarized ammeter remains at zero. On the contrary, it deviates in one direction or in the other if, after the whole system has rotated (the mean position of the needle remaining fixed in space) the two half-periods, that is to say the durations of the closing of the contacts of the relay in one direction or in the other, are no longer equal. The ammeter thus becomes a head indicator, its deviation being function of the angular divergence from the chosen direction.

This index 34 can in its turn, owing to the presence of the contacts 35 and 36, close the circuit of a follow up motor 37 having two directions of rotation which, by means of a worm 38 for instance, and of a wheel 39 on the shaft of which the entire system is assumed to be mounted, will bring back the latter to the position north-south, thus constituting a compass. The ammeter

32 can be located at any distance from the remainder of the apparatus and constitutes a distant head indicator. As regards the telecompass, it can be obtained by transmitting to a distance, by any one of the known methods, the position of the wheel 39. In this form, the coils 28 and 29 and the three contacts 21, 23 and 24 together replace the gears and pinions of Figs. 1 and 2 and form the electrical equivalent thereof. As already intimated, when the needle 20 swings in either direction, it closes the circuit of one of the coils 28, 29 and also that of either one or the other corresponding portion 25 or 26 of the solenoid 25' and thereby correspondingly shifts the relay core 26' to the left or the right so as to shift contacts of relay 27 of battery or current source 31 into closing contact with either pair of the reversing relay contacts 27'. As the relay circuit of current source 31 is connected to the polarized meter 32, the direction of the current coming from source 31 will determine which of the two contacts 35 and 36 of the circuit of the follow up motor 37 will be closed by indicator contact 34, causing corresponding rotation of worm 38 in the one or the other direction and consequent corresponding operation of worm gear 39 and its shaft to readjust and restore the apparatus to zero position with respect to needle 20.

The diagram of Fig. 4, which shows a modification of that of Fig. 3, and serves substantially the same purpose as the system of said Fig. 3, can also be contemplated for maintaining the movement, which allows use of a single contact on the magnetic needle and a single winding 47, the contacts 40 and 41 close the circuit of the electromagnet 42 which actuates the cam wheel 43 through the medium of a pawl and a ratchet wheel. At each impulse, the contacts 44 reverse the current of the amperemeter 45, and maintain desired movement of the needle, whereas the contact 46 only closes the circuit of the winding 47 once in two half-oscillations of the needle.

The desired movement of the needle according to the invention can also be maintained by using the asymmetry of the contact between the needle 50 and the tongue 51 according to the partial view of Fig. 5. The rest of the system can resemble Fig. 3. The effect of the current can be annulled during the contact α^1 , by providing that, for an angle

$$\frac{\alpha^1}{2}$$

the needle is parallel to the magnetic axis M—M of a winding (not shown), whereas for the angle α^2 of the contact different from α^1 , there is necessarily a driving torque exerted on the needle. This axis of the winding will form with the longitudinal axis of the needle at the dead centre, an angle

$$\frac{\alpha^1}{2}$$

In this form, which is also electrical, the gears and pinions of Figs. 1 and 2 are replaced by the contacts 40, 41, the solenoid 42 and the coil 47 and their circuits, etc.

Pneumatic Apparatus (Fig. 6), or as indicated in the drawings, Figs. 6a and 6b show a pneumatically operated escapement in this form which functions as the oscillating means in contrast with the gears and pinions of the first figure.

In this figure, the needle is actuated by using air jet 60 which directly actuates a paddle-wheel 61 rigid with an escapement wheel 62. The fork

5 of the escapement carries on its extension a blade 63 which alternately intercepts two air jets 64 and 65 placed opposite two nozzles 66 and 67 each connected to a manometric capsule 68 and 69 by a tube of small cross-section. At each oscillation of the fork, the blade 63 alternately intercepts for measurable periods of time the air jets 64 and 65. If these periods of time are equal, both capsules 68 and 69 exert equal stresses 10 on the index 70, and the latter remains in equilibrium. If, on the contrary, these periods of time are unequal, it is obvious that the index 70 will indicate a certain deviation and can serve as head indicator.

15 The nozzles 66 and 67 causing the desired operation or oscillation of the needle can be replaced by a small turbine or bladed wheel 71, Fig. 7, which rotates in one direction or in the other according to the relative periods of time it is subjected to the jets 64 and 65. The number of revolutions effected by said wheel transmitted by the worm 72 and worm wheel 73, for instance, can be indicated by an index and serve as an indicator. The rotation of the paddle-wheel can be used for causing the entire device to rotate about a vertical axis due to the presence of the worm 72 and the worm wheel 73 and for restoring it to the north-south position, thus providing means serving as a compass.

20 The swinging or oscillating movement of the magnetic needle according to the invention (Fig. 8) can also be directly maintained by an air jet without the intervention of an escapement. The needle 80 carries an extension 81 at the end of which pivots a blade 82 about an axis parallel to that of the needle. This blade carries two arms 83 and 84 the ends of which come in contact with a fixed cam 85 of such a shape that every time the blade passes in front of the air jet 86 it assumes a position which allows it to receive an impulse in the suitable direction. A pin 87 rigid with the needle actuates a fork 88 carrying a blade 89 the function of which is exactly the same as that of blade 63 (Fig. 6).

25 By way of constructional example, the description of a distant or remote observation head indicator according to the invention, of particularly simple construction, will now be given.

30 A magnetic needle 100 (Fig. 9) is also maintained in desired oscillation by a lever escapement the cogs 101 and 102 of which are metallic, the lever itself being made of insulating material. The power driving the escapement wheel, also metallic, can be of any kind, and may include a spring with a set of wheels similar to that of a watch.

35 The teeth 101 and 102 are each electrically connected by a spiral or flexible wire 103 and 104, to a member 105 and 106 insulated from the body of the apparatus. By the action of the escapement, the current passes alternately through one or the other cog in the circuit of which are respectively inserted the windings, in reverse direction, of a polarized milliamperemeter 107. According to the invention, the periods of rest equal or different on the cogs will leave the milliamperemeter at zero or will cause it to indicate a deviation as soon as the head chosen, is no longer followed. A single electric cell 108 is sufficient, and a resistance 109 of a few hundred ohms is inserted in the circuit. Of course, amperemeters of various responsiveness can be inserted in the circuit.

40 While Figs. 7 and 8 show modifications or simplifications of the pneumatic operation replacing

the gear and pinion operation of Figs. 1 or 2, in Fig. 9, the gears and pinions are replaced by an electromechanical escapement which in this form serves to produce the desired oscillation of the needle.

The known art devices, such as magnetostriction, variation of magnetic permeability, photo-electric cell, variation of frequency of high frequency or low frequency circuits, can be used for maintaining the oscillation of the magnetic bar, and for controlling the movement of the needle.

What I claim as my invention and desire to secure by Letters Patent is:

1. In a dynamic compass having an oscillating pivoted magnetic needle and actuating means imparting alternately and opposite driving impulses thereto at two points equally spaced, at opposite sides of the mean position of said needle, the combination of indicating means showing the orientation or changes of orientation of a movable support or craft carrying said compass, follow up control means for controlling said indicating means including a control member rigidly associated with the magnetic needle at one side intermediate the ends thereof, operating means disposed adjacent to said control member effective to correspondingly influence the actuating means according to the oscillations of said needle and impart any difference occurring between the durations of the opposite oscillations imparted to the needle on either side of its position of rest when said latter position varies with respect to the mean position of the operating means.

2. Dynamic compass according to claim 1, wherein the control member includes an arm angularly rigid with the needle, and the operating means includes a rocking fork actuating said arm, the arm and the pivot of said needle being located on a line coinciding with the mean position of a fork when the needle is on the lubber's point.

3. Dynamic compass according to claim 1, wherein the control member includes an arm angularly rigid with the needle, and the operating means includes a rocking fork actuating said

arm, the arm and the pivot of said needle being located on a line coinciding with the mean position of a fork when the needle is on the lubber's point or a north and south position, and wherein 5 a freely journalled pinion mounted upon the end of the fork opposite the needle, two spaced driving pinions, and means for constantly rotating the same in opposite directions said means being located symmetrically with respect to the mean

10 position of the fork so that oscillation of the fork will cause alternate engagement of the pinion thereon with the spaced driving pinions and impart opposite rotary impulses to said pinion upon said fork, and a gear concentric with the axis of 15 rotation of said fork meshing with the last mentioned pinion having means for imparting the algebraic sum of the rotations to said last mentioned pinion being transmitted to the indicating means.

20 4. Dynamic compass according to claim 1, wherein the operating means include electrical means for producing an alternating magnetic field with two spaced contacts, while the control member includes means associated with the needle capable of alternately closing said contacts in

25 order to energize said magnetic field accordingly, and the indicating means including electric apparatus of the polarized ammeter type, the relative location of said magnetic field and said contacts with respect to the needle causing the relative durations of the closing of said contacts to 30 depend on the mean position of the needle with respect to the lubber's point.

5. Dynamic compass according to claim 1, 35 wherein the operating means includes a movable member imparting oscillations to the needle, two opposed supply means for fluid under pressure, means operatively associated with said movable member for controlling said supply means and causing the latter alternately to actuate the indicating means, and means associated with said operating means causing said indicating means to have a differential operation and to be capable of operation by said fluid supply means.

JEAN-LÉON REUTTER.
